UNITED STATES PATENT OFFICE.

EDWIN D. CHAPLIN, OF NEW YORK, N. Y.

ELECTRIC CONDUCTOR.

1,291,406.

Specification of Letters Patent. Patented Jan. 14, 1919.

Application filed February 8, 1915. Serial No. 6,689.

To all whom it may concern:

Be it known that I, EDWIN D. CHAPLIN, a citizen of the United States, residing in New York, in the county of New York and State of New York, have invented certain new and useful Improvements in Electric Conductors, of which the following is a specification.

A principal object of the present improvements is to furnish electric conductors which shall combine the properties or qualities of being fireproof and waterproof while having a sufficient amount of flexibility for meeting ordinary and unusual requirements, and also be a good insulator.

A further object is to provide for a requisite insulation while avoiding the use of substances which on being unduly heated, whether by the action of electric elements or by external gases, will result in a pressure combustion or in a distillation of materials forming noxious gases of a dangerous character.

It will be remembered in this connection that when insulating materials are subjected to incomplete combustion or to distillation as occurs for instance in feed cables, dangerous gases are sometimes formed in large quantity, especially when the insulating materials consist of rubber or other compounds of vegetable origin such for instance as combinations including "rubber substitutes" as are manufactured from oils or other materials.

These and other features, capabilities and advantages of the invention will appear from the subjoined detailed description of one specific embodiment thereof illustrated in the accompanying drawings in which—

Figure 1 shows a short portion of a conductor made in accordance with my present invention, some parts being broken away for more clearly illustrating a preferred construction thereof.

Fig. 2 is an end view as seen from the right hand of Fig. 1.

Figs. 3, 4 and 5 are detail views illustrating relative features and modifications of construction of the gap-forming member as hereinafter more fully explained.

Fig. 4* is a fragmental end view of the segment illustrated in Fig. 4.

Fig. 6 is a diagrammatic view corresponding to Fig. 1 for illustrating the manner in which the several components of the conductor are shifted or rearranged in their

relative positions when the conductor is forcibly bent to a relatively small curvature.

Figs. 7 and 8 are views corresponding to Figs. 1 and 2 for illustrating the further feature of my invention whereby a leading wire and a return wire may be arranged within the same insulation core and outer casing therefor.

Fig. 9 is a view similar to Figs. 2 and 8 illustrating how the construction may be arranged for using a plurality of conductors greater than two and with a non-circular cross sectional form of the conductor.

My improved electric conductor or conduit may be briefly described as comprising in its more simple forms a conducting wire which will ordinarily be located in the center of the conduit and may consist of a single wire or of a plurality of wires twisted together in a well known manner; an outer tube or casing of suitable character and preferably of ductile metal which for ordinary practice may be lead; and, an intervening gap-forming core consisting of mineral bodies of improved construction arranged in a continuous series within the outer tube or casing and provided with a passageway for the conducting wire or cable. Thus the cable is built up of members assembled together in an organized arrangement and consisting wholly of materials not subject to distillation whereby the formation of dangerous gases cannot result.

Referring to Figs. 1 and 2, 1 designates a tubular casing preferably of lead or similar ductile metal while 2, 2 indicate a series of insulating bodies of the general character of disks arranged in a continuous series and having central openings 3 for the conducting wire 4. This wire is indicated in the drawing as being in the form of a small cable made up of a plurality of small wires twisted together in the usual manner. The insulating bodies 2 are composed of any suitable mineral composition, preferably of earthenware or porcelain of a kind substantially such as now commonly employed in making articles for use in electric devices such as switch bases, and the like.

One feature of my present invention relates to the insulating members 2 which have the function primarily and principally of forming the required "gap" between the conducting wire 4 and the inside of the outer casing 1 whereby to prevent the escape of the electric current from the

said wire 4 to the outer casing 1. A further feature relates to the construction and arrangement of the members 2, 2 of the insulating core whereby a large amount of 5 flexibility may be secured so that the completed conductor may be curved to a considerable extent on an unusually small radius without subjecting the ductile outer casing 1 to an excessive amount of deformation. In bending the ductile tube or casing 1 such as indicated at 6 in Fig. 6, it is well known that it is desirable to effect the bending in such a manner that one side of the tube will be compressed the same amount 10 to which the other side is extended so that the flexure of the conductor considered as a whole will occur along the neutral axis which is about central of the conductor. As a means for providing for such a proper 15 action or flexure, I prefer to employ gap-forming disks or members in which each one has a relatively convex surface on one side and a corresponding concave surface on the other side so that when two of these 20 members or disks are turned one against the other, one of them may be said to form a socket bearing against which the other one operates with a motion similar to that of a ball and socket joint. In this manner 25 each of the gap-forming members moves so to speak about a central point or axis and by a relatively turning movement about such point while these points as 7, 7, Fig. 6, are located approximately in a longitudinal axis which is about central to the 30 conductor. The features here described are illustrated in diagram in Fig. 6 where the successive members 2, 2, 2, are shown turned one upon another for bringing the 35 series into a curvilinear arrangement in such a manner as to secure the desired curvature without an elongation of the conductor as measured along the central axis thereof. 40

45 As a means for more fully securing the described results and mode of action, I make the said convex and concave contacting surfaces of the disks,—as clearly shown and disclosed in the sectional portions of 50 Figs. 1 and 6,—of a spherical form, and also make said surfaces as portions or zones of geometric spheres of the same size which intersect in such a manner that in the sectional view in Fig. 6 the circular line of 55 the convex surface comes near to the center of the circle, or circular line, of the next following convex surface. Also, in connection with that relation and form of the disks, I form the central opening for the 60 conductor 4, of a double bell-mouth shape or construction,—as clearly shown in Fig. 6,—so that the core 4 will bear entirely against surfaces which are longitudinally “rounded” and transversely concaved, for 65 thereby aiding in the regular and even

curvature of said core, while avoiding sharp corners.

The assembling of the several component members of the cable may be performed in several different ways. For instance, the 70 wire or cable 4 may have the series of insulation members 2, 2 assembled thereon by slipping these members over one end of the wire and then sliding them along into a compact series. In practice, this method 75 may require that the insulation members will be applied by machinery in an automatic manner, and for this purpose I have devised a machine especially adapted for carrying out this method of making the 80 conductors. After the conductor wire 4 has the insulation members 2, 2 assembled thereon, the outer covering 1 may be applied in any convenient or suitable manner as for instance by forming the same upon the insulation core (this comprising the said members 2, 2) after the manner now employed for covering electric conductors and cables with a lead casing. This method being well known will not require particular 85 description. I prefer, however, to apply the lead casing by making the same of sheet lead wrapped about the cable and fused together along the joint by the use of appliances now well known in the formation of tubes for other purposes, thus avoiding the operation of drawing the metal into tubular form.

In Figs. 1 and 2 I have shown the insulation members 2, 2 consisting of disks 100 having spherical surfaces where the members contact and move one upon the other and these members are there shown each made integral, that is, in the form of a disk. In some cases, however, each of the 105 insulation members may be composed of two parts put together so as to form a disk. This construction is indicated in Figs. 3 and 4 which are therefore supplemental to Figs. 1 and 2. In Fig. 3, the insulation disk 110 D is shown formed of the two parts d and d' and these may be duplicates of each other, or if preferred, they may be made in a manner so that one supplements the other. The portion d of the complete disk D is 115 shown in Figs. 4 and 4^a as seen from left hand end in Fig. 3, and this arrangement of said device being for the purpose of illustrating the preferred manner of forming the parts d and d', so that they will interlock and thereby be located one upon the other in a proper manner. When the insulation disks D are in segments or separable parts in the manner here illustrated, they may be readily applied to the central 120 wire 4 by hand or otherwise and without the necessity of sliding them into place as when the disks are integral.

Instead of forming the disks as in Figs. 1 and 2 or in separable and complementary 130

sections as in Figs. 3 and 4, these gap-forming members may in some cases be formed of a single piece but of an incomplete circular form as shown, for instance, in Fig. 5 where an open space or slot is made therein at 5 by means of which the disk D' may be passed over the central wire 4 when assembling the insulation core thereon. In practice, when using the form D' of the core members, it will, of course, be desirable to apply these disks in miscellaneous positions circumferentially of the wire so that contiguous core members will have the said openings in non-coincident positions relative to each other and thus avoid the accidental forming of an opening of any considerable length longitudinally of the core through which the central wire might by some accident become misplaced. Any such objection is overcome by turning the disks D' to different circumferential positions so that the said openings will preferably come in transverse directions as regards any pair of contiguous core members. In practice, any turning of the core members after the outer casing is placed thereon may be prevented by forming slight indentations as 9, Fig. 5, in the periphery of the gap-forming disks D', so that when the lead casing is drawn into place the metal thereof will slightly engage or enter into such depressions 9 and thus effectually lock all of the core members in their proper relative positions.

It is believed that usually the circular peripheral form of the insulation members as indicated, for instance, in Figs. 2 and 3 will be preferable, but in some cases, if desired, these members will be made of an oblong peripheral outline either elliptical or otherwise, as indicated, for instance, in Figs. 8 and 9, the latter figure showing the insulation member D² of substantially a triangular form. The elliptical form D², as indicated in Fig. 8, is especially intended for use in my improved conductors when these are made in small sizes as required, for instance, in electric lighting and for signaling lines and the variety of analogous purposes. The arrangement of the details as indicated in Figs. 1 to 6 inclusive, is thought to be especially adapted for conductors used in connection with power lines and especially for use in underground conduits and particularly such conduits as are required in subways and tunnels.

Figs. 7 and 8 illustrate more especially the form and arrangement of my present improvements especially intended for use in small conductors, but it will be understood that the disks or insulating members D² may, if desired, be of circular peripheral form instead of having the elliptical form shown in Fig. 8. However, the use of this elliptical form has the advantage of saving mate-

rial and also indicating to the buyer that the conductor is of a two-wire construction. The size and form of the openings in the disk D² through which the respective wires 4, 4, pass as indicated in the sectional portion of Fig. 7, will, in practice, be arranged for permitting such an amount of curvature or flexibility of the cable as may be desired for the particular purposes for which the cable may be designed in any particular instance. It should be understood in this connection that a relatively greater amount of flexibility or bending capacity may be secured by making the insulation blocks, in either of the arrangements illustrated, to occupy a relatively short space longitudinally of the conductor.

The insulation disks 2 forming the articulated core member of the construction illustrated in Figs. 1 and 6 are substantially spherical bodies, each having a concave spherical socket 10 formed on one side thereof, the central opening 3 being disposed axially of such disk, terminating at one end in the center of said spherical socket 10, and as it approaches its ends in each direction enlarging progressively. The remainder of the surface of the disk is substantially a spherical convex surface 11 so that when these disks are in position on a cable 4, the arrangement is such that the spherical concave surface 11 of one disk will be disposed in the spherical convex socket 10 of its adjacent disk, so that these disks together can have a substantially universal movement relative to one another, and the enlarged ends of the openings 3 will facilitate the angular displacement of such disks 2 relative to the cable 4 which occurs when the conductor is being bent as shown in Fig. 6.

In the form of disk shown in Figs. 3, 4 and 4^a, the segments d and d' together form a disk which has a conformation substantially that of the disk illustrated in Figs. 1, 2 and 6. These segments d and d' are identical with one another, each comprising one-half of the complete disk 2 and dividing the said complete disk 2 along a plane that passes axially through the opening 3. Each of the disks d and d' therefore has two ends to engage with two corresponding ends of its complementary segment, in which there are formed interlocking members, one end having an elongated recess 12, and the other end having an elongated lug 13 both extending transversely of the complete disk 2, and the recess 12 corresponding to and being formed to receive the lug 13 of its complementary segment.

The disk D² illustrated in Figs. 7 and 8 has a somewhat elliptical conformation in the elongated portion of which there is formed a spherical socket 14 on one side thereof, while the remainder of the surface of said disk is substantially convex. Ex-

tending through said disk D^2 , there are formed two openings 15, 15 to take the place of the single opening 3 of the disk 2 illustrated in Figs. 1, 2 and 6, such openings 15 being substantially parallel with one another and terminating at one end in the socket 14. Similarly, these openings 15, 15 as they approach their ends in both directions enlarge progressively for the purpose already set forth. The disks D^2 are thus equipped to receive two wires and will have a special utility for lighting systems and the like, in which cases the two wires may be the leading and the return wire.

15 The disk D^3 , illustrated in Fig. 9, is substantially triangular in cross section, which form is especially adapted to form core members through which three wires are to be extended, for which purpose there are provided three openings 16, 16 and 16. The disk D^3 has also formed in one of its ends a spherical socket 17 to receive the convex end of an adjacent disk D^3 in which socket 17 one series of the ends of said openings 16 terminate.

20 It is obvious that various changes and modifications may be made to the details of construction without departing from the general spirit of the invention.

25 30 I claim:

1. The herein-described electric conductor having an outer ductile casing, and having a gap-forming core disposed in said casing and composed of mineral bodies having a diameter greater than their length and formed convex on one side and concave on

the other side thereof, there being openings in said mineral bodies which together form a continuous passageway in such core, each said mineral body having said convex and 40 concave faces of spherical shape and conforming to similar faces of the adjacent mineral bodies, for facilitating a practically free movement of said bodies relative to one another, said openings as they approach 45 their ends enlarging progressively and each having its smallest diameter midway between said faces; and a conducting wire disposed in said passageway, substantially as 50 set forth.

2. An electric conduit having an outer casing of ductile metal, a gap-forming core disposed in said casing and composed of a plurality of mineral bodies convex on one side and concave on the other side thereof, 55 there being openings in said mineral bodies which together form a continuous passageway in such core, a conducting wire disposed in said passageway, each mineral body comprising a segmental portion to permit positioning of such mineral body on said conducting wire through a movement transverse to said conducting wire, and a series of relatively shallow depressions longitudinally disposed in the periphery of said mineral 60 body to be engaged by the outer casing and frictionally hold said mineral body against rotation.

EDWIN D. CHAPLIN.
